REINFORCED LUGGAGE BOX

Frank Serpico, Philadelphia, Pa.

Application July 17, 1948, Serial No. 39,217

5 Claims. (CL. 217—5)

1

This invention relates to luggage boxes or frames formed by the upper and lower halves of a box and has for an object the provision of reinforcing corner strips which are supported at their ends by two sides of the box structure.

For many years suitcase frames, generally consisting of a wooden box having a body portion and a cover portion, have been constructed of strong, lightweight wood with dovetailed or tongue-and-groove joints along the four vertical corners. The closure for the cover portion has been secured in place by gluing it to angle-reinforcements also adhesively secured to the side of the box. Such angle-reinforcements have been terminated inside the ends of the box and have been manually moved into alignment with the upper edge prior to application of gluing clamps. Workmen have not always properly aligned the angle-reinforcement, and in the event of an imperfect bond, there has been a tendency for the angle-reinforcement to break loose causing a disproportionately large number of rejects, boxes which are not suitable for completion into a finished piece of luggage.

In carrying out the present invention in one form thereof, corresponding vertical sides of both the body portion and cover portion of the box are provided with 45 degree angle recesses into which angle-reinforcements may be guided into exact alignment. Accordingly, the task of placing the angle-reinforcements in the exact position required has been greatly simplified, and even with unskilled labor the number of rejects due to faulty alignment has been greatly decreased. Additionally, by overlapping the ends of the angle-reinforcements with the ends of each box portion, great strength is added to the box as a whole since the ends of the reinforcement, being supported, carry a substantial part of the load, thus reducing the forces which may be applied to the angle strip and which might result in breakage of the adhesive bond. Surprisingly enough, the additional cost of milling or otherwise providing the corner notches or recesses is substantially or entirely offset by increased production due to the greater ease of alignment, and is certainly offset by the additional saving in rejects.

For a more complete understanding of the invention, reference is to be had to the following description taken in conjunction with the accompanying drawing in which:

Fig. 1 is a perspective view of a luggage frame embodying the invention and in the form in which it is ready to receive a cover of fabric or of leather or of other material;

2

Fig. 2 is an exploded perspective view of a fragmentary part of a corner of the lid or cover portion;

Fig. 3 is an enlarged perspective view of a corner section of parts of Fig. 2 in the assembled position; and

Fig. 4 is an end view of a corner of the box of Fig. 1 with that part of the corner which is sanded away shown in dotted lines.

- 10 Referring to the drawing, luggage of the better class including suitcases, overnight bags, and the like, comprises a box 10 having a cover portion or lid 11 and a body portion 12. Each of portions 11 and 12 are made by assembling and bonding together the sides and ends, preferably provided with tongues and grooves which, when adhesively bonded together, form strong rectangular frames open at the tops and bottoms. These open rectangular frames are then closed.
- 15 20 Heretofore, the bottom of the body portion 12 and the closure for the lid or cover portion 11 have been secured in place by first gluing angle-reinforcements to the vertical sides of the box, the exposed faces of each pair of reinforcements being respectively flush with the upper and lower edges of the box. Each closure is then adhesively secured to the box and the faces of the angle-reinforcements.

In carrying out the present invention in one form thereof, after the two sides 13 and 14 have been adhesively secured together at the tongue-and-groove joints, the end members 13 at the corners adjacent the side walls 14 are milled away, each cut-out portion thereby providing 45 degree recesses or notches 15 into which may be placed angle-reinforcements 16. As shown in Fig. 2, all the parts have been separated for easy identification thereof.

While it would be possible to precut each end member, such as the end member 13, at 45 degrees to provide the recesses at 15, the foregoing method is preferred where such recesses are milled with reference to the upper edges of the ends 13 and the sides 14. This preferred method assures greater accuracy in the resulting alignment of the angle-reinforcement 16 with the side 14. As best shown in Fig. 4, it will be seen that the angle-reinforcement 16, in end view, comprises an isosceles right triangle, which is the preferred form. In assembling the angle-reinforcement 16 to the side 14, it is only necessary adhesively to coat the face 16a, and if desired also to coat the angle edge 15 of each of the ends 13. The angle-reinforcement is then dropped into the recess and gluing clamps applied to hold it in place. As soon as the glue sets and the bond is

completed, the closure 20 may be adhesively secured to the aligned upper edges of the ends 13, the sides 14 and the added angle-reinforcements 16. A typical corner is illustrated in Fig. 4, the part in broken lines illustrating the appearance of the corner prior to the rounding of the longitudinal side.

After the closure 20 has been bonded to the sides, the assembly as a whole is taken to a suitable sand wheel and the corners rounded as shown in full lines in Fig. 4. Not only are the longitudinal edges rounded, but also the side edges so that the outer surface of the box presents smoothly rounded corners throughout the periphery of the box. Frequently, the cover or lid is rounded to a greater degree than the body portion of the box.

After completion of the body portion 10 and the cover portion 11, in the manner described above, they are frequently shipped as a box unit to different technicians who cover the wood frames or boxes with suitable material. The wood is soft enough so that the fabric or leather covering may be stitched directly to the box. The stitching frequently is through both the sides and the angle-reinforcements. In the past it has frequently occurred that the length of the angle-reinforcements has been somewhat less than the length of the sides of the box, thus leaving a small gap between the end of the box and the end of the angle-reinforcement. Whenever this occurs, there arises the possibility that the stitching needle will enter adjacent the end of the reinforcement and thus be deflected to one side, resulting in needle breakage. This has occurred often enough to be a source of considerable difficulty and annoyance, because it not only increases the cost due to the needle breakage, but also greatly slows up operation and sometimes makes it difficult to complete the seam without showing the damage done as a result of the broken needle.

In accordance with the invention, the fact that each angle-reinforcement extends outwardly into overlapping relation with the sides and is coextensive in length with the sides of the box eliminates entirely the possibility of needle breakage because the angle-reinforcements may be too short. Additionally, the angle-reinforcements being rigidly supported at the ends greatly increase the strength of the box and prevent deflection under applied force to the closure member 20 which results in progressive breakage of the adhesive bond. As a result of the present invention, the number of rejects has substantially and entirely disappeared and is no longer a factor in the cost of manufacture.

Aside from the foregoing advantages, the extension of the angle-reinforcements through the side walls has resulted, after rounding of the corners including the reinforcements, in a greatly enhanced appearance of the four corners of the box. Each corner, as best shown in Fig. 3, provides an appearance which is suggestive of the fact that the angle-reinforcement 16 forms an interlocking engagement with the end 13. This appearance results from the fact that the rounding process produces a double curvature at the corner of the end of the angle-reinforcement to which because wider along its base appears to interlock the side and end walls and does, in fact, result in a better, stronger box.

While modifications of the invention have been described, it is to be understood that further

variations may be made within the scope of the appended claims.

What is claimed is:

1. For luggage, a box comprising sides, ends and a closure, right-angle reinforcing members coextensive in length with said sides and each adhesively secured to the inner surface of a side of the luggage box along one right-angle surface, the other right-angle surface of each member being coplanar with the closure-engaging edges of said ends to provide additional bonding surfaces for said closure, said ends having 45 degree angle cut-outs for receiving and guiding and supporting the ends of said angle reinforcing members, the corner-intersecting extremities of said sides and ends being secured together in tongue and groove relation, and means including an adhesive for bonding the inner surface of said closure to said angle reinforcing members and to the coplanar edges of said ends, said reinforcing members after rounding of the corners of said luggage box adjacent said closure presenting an unbroken surface and at the corners an appearance of interlocking relation between each reinforcing member and each corner-intersecting side and end.

2. A luggage box comprising side walls rigidly secured together, a closure disposed in engagement with the side walls to close one end of said box, a pair of opposed walls having their corners adjacent said closure angularly cut away, an angle reinforcing member coextensive in length with the box between said cut-away corners for extension into said angle cut-outs for support of the respective ends thereof by said opposed walls, said angle member having angular faces respectively in supporting relation with said closure and with the adjacent wall which interconnects said opposed walls.

3. A luggage box comprising side walls rigidly secured together, a closure disposed in engagement with the side walls to close one end of said box, a pair of opposed walls having their corners adjacent said closure angularly cut away, an angle reinforcing member in shape complementary to that of said angle cut-outs and coextensive in length with the box between said cut-away corners for extension into said angle cut-outs for support of the respective ends thereof by said opposed walls, said angle member being bonded at its ends to each of said opposed walls, along one side to the adjacent side wall which interconnects said opposed walls and presenting the other side thereof into bonding relation for application thereto of said closure member.

4. A luggage box comprising side walls rigidly secured together, a closure disposed in engagement with the side walls to close one end of said box, a pair of opposed walls having their corners adjacent said closure angularly cut away, said closure having its inner surface flat against the edges of said opposed walls, an angle reinforcing member in shape complementary to that of said angle cut-outs and coextensive in length with the box between said cut-away corners for extension into said angle cut-outs for support of the respective ends thereof by said opposed walls, said angle member having angular faces respectively in supporting relation with said closure and with the wall adjacent said closure which wall interconnects said opposed walls.

5. A luggage box comprising side walls rigidly secured together, the corner-intersecting extremities of said side walls being secured together

in tongue and groove relation, a closure disposed in engagement with the side walls to close one end of said box, a pair of opposed walls having their corners adjacent said closure angularly cut away, an angle reinforcing member coextensive in length with the box between said cut-away corners for extension into said angle cut-outs for support of the respective ends thereof by said opposed walls, said angle member having angular faces respectively in supporting relation with said closure and with the adjacent wall which interconnects said opposed walls and adhesively secured thereto.
